UNITED STATES PATENT OFFICE.

RUDOLPH F. SETTLEAGE, OF ST. LOUIS, MISSOURI.

REVERSING-GEAR FOR WASHING-MACHINES.

1,347,975.

Specification of Letters Patent.

Patented July 27, 1920.

Application filed August 29, 1919. Serial No. 320,563.

To all whom it may concern:

Be it known that I, RUDOLPH F. SETTLEAGE, a citizen of the United States, residing at St. Louis, Missouri, have invented a certain new and useful Improvement in Reversing-Gears for Washing-Machines, of which the following is a full, clear, and exact description, such as will enable others skilled in the art to which it appertains to make and use the same, reference being had to the accompanying drawings, forming part of this specification.

My invention relates to new and useful improvements in reversing gearing, and particularly to that type wherein the rotary motion of a continuously operating member such as a driving shaft is transmitted to a driven member and causes the latter to be rotated a certain number of revolutions in one direction and then reversely rotated for a corresponding number of revolutions, such action being entirely automatic and effected through certain instrumentalities that are dependent for operation upon the continuous rotary motion of the driving shaft.

The principal objects of my invention are, to provide a reverse gearing of the character outlined that possesses the desirable features of simplicity, durability, efficiency, and compactness of structure; further, to provide a construction which is positive in action and practically noiseless while in operation; and further, to provide simple manually controlled means for shifting a portion of the reverse gearing into neutral or inoperative position, thereby breaking the connection between the driving shaft and the driven shaft.

The type of mechanism herein illustrated and described is particularly designed for use upon washing machines utilizing a rotary clothes containing drum or cylinder, although it will be readily understood that practically the same form of mechanism can be advantageously used wherever it is desired to effect a rotation of a shaft for a number of revolutions in one direction and then for a corresponding number of revolutions in the other direction.

With the foregoing and other objects in view, my invention consists in certain novel features of construction and arrangement

of parts, hereinafter more fully described and claimed, and illustrated in the accompanying drawings, in which—

Figure 1 is an elevational view of a washing machine equipped with a reversing gear of my improved construction.

Fig. 2 is an enlarged cross section taken approximately on the line 2—2 of Fig. 1.

Fig. 3 is a detail section taken approximately on the line 3—3 of Fig. 2.

Fig. 4 is a detail section illustrating a ratchet wheel centering device made use of in my improved gearing.

Fig. 5 is a section taken approximately on the line 5—5 of Fig. 2.

Fig. 6 is a section taken approximately on the line 6—6 of Fig. 2.

Referring by numerals to the accompanying drawings which illustrate a practical embodiment of my invention, 10 designates the tub portion of a washing machine, the same being supported on a suitable framework, and mounted for rotary movement within said tub is the usual clothes containing drum or cylinder (not shown), and which latter, it will be understood, rotates first in one direction and then in the other. One end of this drum is provided with a socket plate or bracket 11 that is recessed to receive the angular head 12 of a stub shaft 13 the latter being mounted for rotary movement in a bearing 14 that is formed on the central portion of a plate 15. This plate is positioned immediately over an opening 16 that is formed in one of the side walls of the tub 10 and said plate being secured to said wall in any suitable manner. Secured to this plate and projecting outwardly therefrom is a substantially cylindrical housing 17 to the outer portion of which is removably secured a cover plate 18, and formed on said housing 17 and cover plate at diametrically disposed points are bearings 19 for a shaft 20. This shaft is positively driven in any suitable manner, preferably from an electric motor (not shown) that is located on a suitable support on the lower portion of the frame for the tub.

Loosely mounted on the driving shaft 20 within the housing 17 are oppositely arranged beveled pinions 21 which are con-

stantly in mesh with the teeth of a beveled gear wheel 22, the latter being fixed on the stub shaft 13.

A sleeve 23 is splined upon the driving shaft 20 between the pinions 21 so that it will rotate with and slide lengthwise upon said shaft and the ends of this sleeve are provided with lugs or teeth 24 that are adapted to engage with corresponding lugs 10 or teeth 25 that project from the faces of the pinions 21.

Formed in the periphery of sleeve 23 and at a central point thereupon is an annular groove 26 in which is positioned the arms 15 of a yoke 27 and which latter is provided at one end with a stud 28. Formed integral with and projecting outwardly from the axis of this stud is a short pin 29 that is positioned in a short transversely disposed 20 groove 30, the latter being formed in the inner face of the central portion of cover plate 18.

Formed in stud 28 to one side of pin 29 is a longitudinally disposed bore or recess 31 25 and positioned therein is a spring-pressed ball 32. Formed in the inner face of the cover plate 18 and at a point directly opposite the center of groove 30 is a recess 33 which serves as a seat for the ball 32 when 30 the stud 28 and parts carried thereby are shifted to a neutral position.

Loosely mounted upon stud 28 and positioned immediately adjacent to the cover plate 18 is a disk 34 and formed on the inner 35 face thereof adjacent to its periphery is a series of ratchet teeth 35 that are adapted to be engaged by a single tooth 36 that is formed on sleeve 23 adjacent to one end thereof.

40 Formed integral with or fixed to the underside of ratchet wheel 34 is a cam disk 37, approximately one-half of the periphery of which is coincident with the circumference of the ratchet wheel 34 as designated by 38 45 and the other half of the periphery of said cam is formed on a circle which is concentric with and substantially smaller in circumference than the larger circumference or periphery 38, said smaller portion of the periphery being designated by the numeral 39.

Fulcrumed on pins or studs 40 which are seated in the cover plate 18 are short levers 41, the free ends of which are rounded as designated by 42, and said rounded ends being adapted to engage the peripheral portions 38 and 39 of the cam. Pivotally connected to the opposite ends of these levers are the outer ends of a pair of toggle links 43, the inner ends of the latter being pivotally connected to a rod 44 which extends through the edge of cover plate 18, and its outer end being provided with a handle 45.

60 The levers 41 and toggle links 43 are constructed so that when the handle 45 and rod 65 44 are pulled outward as illustrated by solid

lines in Fig. 6, the rounded ends 42 of the levers will be spaced apart a distance equal to the distance between a point on the peripheral portion 39 of the cam and a diametrically opposite point on the peripheral portion 38. Consequently as the cam rotates between the rounded ends 42 of the levers, said disk, ratchet wheel 34, and parts carried thereby, will be alternately shifted in opposite directions as the shoulders between the 75 peripheral surfaces 38 and 39 ride onto and off the ends of the levers 41 and during this shifting movement of the cam, it will be guided by the engagement of pin 29 in groove 30.

80 In order to hold the ratchet wheel 34 so that its teeth are retained in proper position relative to the single tooth 36 on the sleeve 23, a spring 46, preferably a short section of resilient wire, has one end seated in the lower end of yoke 27 and the free end of said spring bears on the face of the ratchet wheel between the teeth thereof, thus yieldingly retaining the ratchet wheel in proper position, particularly while the parts of the 90 reversing gear are shifted into neutral position.

The operation of my improved reversing gear is as follows:

Assuming that the driving shaft 20 is in 95 operation and it is desired to set the reverse mechanism so that the clothes containing drum or cylinder will rotate first in one direction and then in the other, the handle 45 is pulled outward to the position shown by 100 solid lines in Fig. 6, thereby moving the rounded ends 42 of the levers 41 toward each other and into engagement with the peripheral portions of the cam 37.

105 As one of the levers bears on the peripheral portion 39 having the smaller circumference and the other lever bears on the peripheral portion 38 having the larger circumference, said cam and parts carried thereby will be shifted so that pin 29 occupies one end of groove 30 and when so positioned the teeth 24 on one end of the sleeve 23 will occupy a position in the path of travel of the teeth 25 on one of the pinions 21, thereby forming a driving engagement between this particular pinion and said sleeve.

110 The rotary motion of shaft 20 is now transmitted through the sleeve 23 to the pinion with which said sleeve is in engagement and from said pinion to beveled gear wheel 22 that is carried by stub shaft 13, and the latter being connected to the drum or cylinder of the washing machine will impart rotary motion to the latter.

115 As sleeve 23 rotates with the driving shaft 20 the tooth 36 on said sleeve will, during each revolution, engage one of the teeth of the ratchet wheel 34 thereby intermittently rotating the latter and when said ratchet 120 125 130

wheel has been rotated approximately one-half a complete revolution, the cam and said ratchet wheel and parts carried thereby will be bodily shifted the length of the groove

5 30 and which shifting action is brought about by the engagement of the peripheral edges 38 and 39 of the cam with the ends of levers 41, it being understood that as the cam is rotated the positions of the peripheral portions having the different diameters will be reversed.

As this shifting of the cam, ratchet wheel and parts carried thereby takes place, the sleeve 23 will be shifted lengthwise upon 10 driving shaft 20 with the result that the connection between said sleeve and the pinion 21 with which it has been engaged will be broken and the opposite pinion 21 will be locked to the corresponding end of the 15 sleeve through the engagement of the corresponding lugs or teeth 24 and 25.

With the parts so positioned, the gear wheel 22, stub shaft 13 and parts carried thereby will be reversely rotated with respect to the direction in which they were 20 previously rotated and this reverse rotary motion will be continued until the ratchet wheel 34 and parts associated therewith have been intermittently rotated approximately 25 one-half a revolution, which action, it will be understood, is brought about by the engagement of the tooth 36 with the teeth of 30 said ratchet wheel, as hereinbefore described.

In the event that it is desired to temporarily render the reversing gear inoperative, certain of the parts thereof are shifted into a neutral position by forcing the handle 45 and rod 44 inwardly to the positions illustrated by dotted lines in Figs. 6, and which 40 movement swings the levers 41 upon their fulerums and moves the rounded ends 42 of said levers away from each other so that their engaging faces are spaced apart a distance slightly greater than the diameter of 45 the peripheral portion 38 of the cam.

When so positioned, the cam and parts associated therewith including the sleeve 23, will take an intermediate position between the pinions 21 with the pin 29 at a central 50 point in groove 30 and with the teeth on the ends of the sleeve 23 out of engagement with the teeth 25 on both beveled pinions 21. The cam and associated parts are yieldingly maintained in this neutral or inoperative 55 position by the engagement of spring-pressed ball 32 in recess 33.

The reversing gear of my improved construction is entirely automatic in operation positive in effecting a periodic reversal of 60 the rotary motion transmitted to a driven member, can be easily and cheaply manufactured, and possesses superior advantages in point of simplicity, durability and general efficiency.

65 It will be readily understood that minor

changes in the size, form and construction of the various parts of my improved reversing gear may be made and substituted for those herein shown and described, without departing from the spirit of my invention, the scope of which is set forth in the appended claims.

I claim:

1. In a reversing gear, a driving shaft, a pair of pinions loosely mounted thereupon, a gear wheel meshing with said pinions, a shaft upon which said gear wheel is carried, a member mounted to slide lengthwise upon and rotate with the driving shaft between the pinions thereon, the ends of which member are adapted to engage said pinions so as to drive the same, a cam, means associated therewith for effecting a movement of the cam in a direction substantially parallel with the driving shaft, and driving connections between said cam and the member that is mounted on the driving shaft between the pinions.

2. In a driving gear, a driving shaft, a pair of pinions loosely mounted thereon, a gear wheel having engagement with said pinions, a shaft carrying said gear wheel, a sleeve arranged to slide lengthwise upon and rotate with the driving shaft and positioned between the pinions thereon, the ends of said sleeve being adapted to engage the pinions to drive the same, a ratchet wheel connected to said sleeve, means on said sleeve for intermittently rotating said ratchet wheel, a cam associated with said ratchet wheel, 100 means coöperating with said cam for bodily shifting the same and associated parts, and means for guiding the movement of said cam in a direction substantially parallel with the driving shaft.

3. In a driving gear, a driving shaft, a pair of pinions loosely mounted thereon, a gear wheel having engagement with said pinions, a shaft carrying said gear wheel, a sleeve arranged to slide lengthwise upon and rotate with the driving shaft and positioned between the pinions thereon, the ends of said sleeve being adapted to engage the pinions to drive the same, a ratchet wheel connected to said sleeve, means on said sleeve for intermittently rotating said ratchet wheel, a cam associated with said ratchet wheel, 110 means coöperating with said cam for bodily shifting the same and associated parts, means for guiding the movement of said cam in a direction substantially parallel with the driving shaft, and means for shifting the cam and associated parts into a neutral position.

4. In a driving gear, a driving shaft, a pair of pinions loosely mounted thereon, a gear wheel having engagement with said pinions, a shaft carrying said gear wheel, a sleeve arranged to slide lengthwise upon and rotate with the driving shaft and positioned 120

between the pinions thereon, the ends of said sleeve being adapted to engage the pinions to drive the same, a ratchet wheel connected to said sleeve, means on said sleeve 5 for intermittently rotating said ratchet wheel, a cam associated with said ratchet wheel, means coöperating with said cam for bodily shifting the same and associated parts, means for guiding the movement of 10 said cam in a direction substantially parallel with the driving shaft, means for shifting the cam and associated parts into a neutral position, and means for holding said cam and associated parts in neutral position.

- 15 5. In a reversing gear, a driving shaft, a pair of pinions loosely mounted thereon, a gear wheel having driving connections with said pinions, a shaft on which said gear wheel is carried, a clutch member carried by the driving shaft and adapted to engage the pinions thereon, a ratchet wheel associated and movable with said clutch member, and means on said clutch member for imparting intermittent rotary movement to said ratchet wheel.
- 20
- 25

6. In a reversing gear, a driving shaft, a pair of pinions loosely mounted thereon, a gear wheel having driving connections with said pinions, a shaft on which said gear wheel is carried, a clutch member carried by the driving shaft and adapted to engage the pinions thereon, a ratchet wheel associated and movable with said clutch member, means on said clutch member for imparting intermittent rotary movement to said ratchet wheel, a cam carried by said ratchet wheel, and means with which said cam is adapted to engage for shifting the clutch member lengthwise upon the driving shaft.

16. 7. In a reversing gear, a driving shaft, a pair of pinions loosely mounted thereon, a gear wheel having driving connections with said pinions, a shaft on which said gear
45 wheel is carried, a clutch member carried by the driving shaft and adapted to engage the pinions thereon, a ratchet wheel associated and movable with said clutch member, means on said clutch member for imparting 50 intermittent rotary movement to said ratchet wheel, a cam carried by said ratchet wheel, means with which said cam is adapted to engage for shifting the clutch member lengthwise upon the driving shaft, and 55 means for shifting said cam, ratchet wheel and clutch member into a neutral position between the pinions.

8. In a reversing gear, a driving shaft, a pair of pinions loosely mounted thereon, a gear wheel having driving connections with said pinions, a shaft on which said gear

wheel is carried, a clutch member carried by the driving shaft and adapted to engage the pinions thereon, a ratchet wheel associated and movable with said clutch member, means on said clutch member for imparting intermittent rotary movement to said ratchet wheel, a cam carried by said ratchet wheel, means with which said cam is adapted to engage for shifting the clutch member lengthwise upon the driving shaft, means for shifting said cam, ratchet wheel and clutch member into a neutral position between the pinions, and means for holding said cam and associated parts in neutral position. 65 70 75 75

9. In a reversing gear, a driving shaft, pinions loosely mounted thereon, a gear wheel having driving connections with said pinions, a shaft upon which said gear wheel is carried, a clutch member arranged to rotate with and slide lengthwise upon the driving shaft between the pinions, a yoke carried by said clutch member, a ratchet wheel loosely mounted on said yoke, means for intermittently driving said ratchet wheel from the clutch member, a cam associated with said ratchet wheel, means with which the cam is adapted to engage to shift the ratchet wheel, yoke and clutch member bodily in a direction substantially parallel with the axis of the driving shaft, and means for positioning said cam engaging means so as to cause the cam and associated parts to assume a neutral position with respect to the pair of pinions. 80 85 90 95

10. In a reversing gear, a driving shaft, pinions loosely mounted thereon, a gear wheel having driving connections with said pinion, a shaft upon which said gear wheel is carried, a clutch member arranged to rotate with and slide lengthwise upon the driving shaft between the pinions, a yoke carried by said clutch member, a ratchet wheel loosely mounted on said yoke, means for intermittently driving said ratchet wheel from the clutch member, a cam associated with said ratchet wheel, means with which the cam is adapted to engage to shift the ratchet wheel, yoke and clutch member bodily in a direction substantially parallel with the axis of the driving shaft, means for positioning said cam engaging means so as to cause the cam and associated parts to assume a neutral position with respect to the pair of pinions, and means for holding said cam and associated parts in neutral position. 100 105 110 115

In testimony whereof I hereunto affix my signature this 27th day of August, 1919.

RUDOLPH F. SETTLAGE.
